UNITED STATES PATENT OFFICE.

WILLIAM ELIOT BARROWS, OF PHILADELPHIA, PENNSYLVANIA, ASSIGNOR
TO THE WELSBACH LIGHT COMPANY, OF GLOUCESTER CITY, NEW
JERSEY.

DESIGN FOR A GALLERY FOR INCANDESCENT GAS-LIGHTS.

SPECIFICATION forming part of Design No. 25,845, dated July 28, 1896.

Application filed May 26, 1896. Serial No. 593,187. Term of patent 14 years.

To all whom it may concern:

Be it known that I, WILLIAM ELIOT BARROWS, a citizen of the United States, residing at the city of Philadelphia, in the county of 5 Philadelphia and State of Pennsylvania, have invented and produced a new and original Design for a Gallery for Incandescent Gas-Lights, of which the following, taken in connection with the accompanying drawings, is 10 a specification.

Figure 1 is a top view of a gallery for an incandescent gas-light, showing my design; and Fig. 2 is an elevational view of the same, also showing my design. These two figures 15 are deemed necessary to properly illustrate my design.

My design relates to configuration or shape, and it is to be stamped or otherwise placed on or worked into that part of an incandescent gas-light which is usually superposed on 20 the air-shutter and carries the globe, chimney, or shade, and which is commonly designated the "gallery."

The leading or characteristic feature of my 25 design may be said to be an ornamental spider mounted upon a hemispherical open fret-work base with an ornamental fillet or band which appears between the two.

a is the spider, whose legs are ornamented 30 by bifurcated ribs b, which appear upon their faces.

c is the fillet, which presents an open-work diamond-shaped appearance, as at d.

e is the hemispherical base, which presents to view foliated openings f, g, h, and i, of 35 which those designated i are considerably larger than the others.

The external aspect or appearance which characterizes my design will be better understood by reference to the accompanying drawings, in which it is clearly illustrated, than by verbal description. Accordingly reference is made to the accompanying drawings for an understanding of such aspect or appearance rather than to the precise shape of the various openings f, g, h, and i, although the fact that the opening i is comparatively larger is 45 important, because it affords means of egress for insects which may fall from the light.

What I claim as new, and desire to secure 50 by Letters Patent, is—

The design for a gallery for an incandescent gas-light, substantially as shown and described.

In testimony whereof I have hereunto 55 signed my name in the presence of two witnesses.

WILLIAM ELIOT BARROWS.
